[57] CLAIM

The ornamental design for a roof-mounted smoke exhaust for use in removing cigarette smoke from the interior of an automobile, as shown and described.

DESCRIPTION

FIG. 1 is a front elevational view of the roof-mounted smoke exhaust for use in removing cigarette smoke from the interior of an automobile showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is an isometric view thereof.

The smoke exhaust has been shown broken away at the upper end of the vertically extending member in FIGS. 1, 2, and 4-7, to indicate indeterminate length.
